UNITED STATES PATENT OFFICE.

LAVEGA SELF, OF PIEDMONT, MISSOURI.

CAR-COUPING.

SPECIFICATION forming part of Letters Patent No. 363,551, dated May 24, 1887.

Application filed April 14, 1887. Serial No. 234,778. (No model.)

To all whom it may concern:

Be it known that I, LAVEGA SELF, of Piedmont, in the county of Wayne and State of Missouri, have invented a new and Improved 5 Car-Coupling, of which the following is a specification, reference being had to the annexed drawings, forming a part thereof, in which—

Figure 1 is a side elevation, partly in section, taken on line *x* *x* in Fig. 4, of a coupling constructed according to my improvement. Fig. 2 is a front elevation. Fig. 3 is an enlarged longitudinal section of the end of one of the couplings, taken on line *y* *y* in Fig. 4; 15 and Fig. 4 is a partial plan view.

Similar letters of reference indicate corresponding parts in all the views.

The object of my invention is to provide a simple and effective device for coupling rail-way-cars which will be entirely automatic in its operation, and will thus relieve the train-men from danger in coupling the cars.

My invention consists in the combination, with the chambered head of the draw-bar, of 25 a spring-pressed follower adapted to hold the pin in an elevated position; also, to hold the link in suitable position for engagement with the draw-head of the adjacent car.

The chambered head *A* of the draw-bar *B* 30 is provided with the usual vertical aperture, *a*, for receiving the pin *C*, and in the chamber of the draw-bar is placed a follower, *b*, provided with the head *c*, between which and the rear wall of the chamber is placed a spring, 35 *d*. The pin *C*, inserted in the aperture *a*, is cut away at its lower end, forming a shoulder, *e*, and is provided with a lug, *f*, projecting laterally from one side in position to rest upon the top of the draw-bar when the pin is 40 withdrawn from the coupling-link, as shown in Figs. 1 and 3. At the side of the hole *a*, in the upper part of the draw-bar, is formed a groove, *g*, which allows of the passage of the lug *f* when the pin drops after being released 45 by the entrance of the link *D* into the draw-bar. Upon the top of the draw-bar is arranged a covering, *h*, for the lug *f*, which is provided with a segmental recess, *f'*, which permits the said lug *f* to turn through a part 50 of a revolution after being lifted through the top of the draw-bar.

The operation of my improved coupling is as follows: By raising the pin *C* so as to bring the lug *f* in the segmental recess *f'* of the covering *h*, and turning the said pin so as to bring the flattened surface thereof against the upper edge of the head *c* of the follower *b*, with the shoulder *e* resting upon the top of the said head, the pin *C* is held in position for engagement with the link *D*, carried by the coupling 60 of the adjacent car. When the link *D* enters the chambered head *A* of the draw-bar *B*, it pushes back the follower *b* and releases the pin *C*, so that it drops through the link *D* and effects the coupling of the cars. The head *c* of 65 the follower *b* is cut away or beveled on its lower part, to enable it to hold the link *D* in a suitable position, so that it will enter the adjacent coupling.

The coupling is uncoupled by withdrawing 70 the pin *C* by means of the rod *i*, extending to the top of the car. The pin *C* is provided with a T-shaped head, *j*, which rests in a transverse notch, *k*, in the covering *h*, and prevents the pin from turning when the cars are 75 coupled, thus always insuring the engagement of the convex side of the lower end of the pin *C* with the lower part of the draw-bar.

To prevent wear in the interior of the draw-head, I have provided a washer, *F*, which is 80 placed in the draw-head and forms a guide for the follower *b*, as well as an abutment for the spring *d*.

The coupling-pin may be turned so that the coupling will not operate, thus enabling the 85 train-men to push the cars without coupling them.

The beveled head of the follower keeps the link always at the bottom of the draw-head, thereby keeping the strain on the pin near the 90 bearing in the hole in the draw-head.

Having thus fully described my invention, I claim as new and desire to secure by Letters Patent—

1. The combination, with the draw-bar *B*, 95 provided with the chambered head *A*, of a spring-actuated follower, *b*, provided with the beveled head *c*, the pin *C*, provided with the shoulder *e* and lug *f*, and the covering *h*, adapted to retain the lug *f* and limit the turning of the pin *C*, substantially as described.

2. The combination, with the chambered

head A of the draw-bar B, of the pin C, provided with the T-shaped head j, and the covering h, having the transverse notch k, substantially as described.

5 3. The combination, with the draw-bar B, having the chambered head A, provided with the aperture a, of the pin C, having the shoulder e and T-shaped head j, the rod i, the

spring-actuated follower b, provided with the beveled head c, and the covering h, having to the segmental recess f' and the transverse notch k, substantially as described.

LAVEGA SELF.
